UNITED STATES PATENT OFFICE.

HENRY W. GAYS, OF ST. LOUIS, MISSOURI.

DESIGN FOR A SILL-POCKET.

SPECIFICATION forming part of Design No. 28,357, dated March 8, 1898.

Application filed January 17, 1898. Serial No. 666,999. Term of patent 14 years.

To all whom it may concern:

Be it known that I, HENRY W. GAYS, a citizen of the United States, residing at the city of St. Louis, State of Missouri, have invented 5 a certain new and original Design for Sill-Pockets, of which the following is a full, clear, and exact description, such as will enable others skilled in the art to which it appertains to make and use the same, reference being 10 had to the accompanying drawings, forming part of this specification, in which—

Figure 1 is a view in perspective, as seen from the front, of my newly-designed sill-pocket. Fig. 2 is a plan view of the same. 15 Fig. 3 is a rear elevational view of the same, and Fig. 4 is a side elevational view of the same.

15 This invention relates to a new and original design for sill-pockets; and it consists, generally stated, in the ornamentation and shape 20 of the same, as will hereinafter be described.

In the drawings, A indicates the base, and B the end wall rising from one end of base A and at about right angles thereto.

b b indicate flanges, which extend the entire height of said end wall B.

The end wall B is ornamented with four cylindrical projections b', arranged in about the four corners thereof, said cylindrical portions each being perforated or formed with 30 an opening b".

Having thus described my design, what I claim is—

The design for a sill-pocket, substantially as herein shown and described. 35

In testimony whereof I hereunto affix my signature, in the presence of two witnesses, this 8th day of January, 1898.

HENRY W. GAYS.

Witnesses:

HUGH K. WAGNER,
F. R. CORNWALL.
